UNITED STATES PATENT OFFICE

HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

BAFFLE FOR PROTECTING SUPERHEATER HEADERS

Application filed March 9, 1928. Serial No. 260,288.

This invention relates to a single pass boiler of the Babcock & Wilcox type, that is provided with a superheater and a baffle for protecting the headers of the superheater against direct impinging of the gases thereupon. At the same time the space between the baffle and the superheater headers is ventilated to avoid danger of explosion. The invention will be understood from the description in connection with the accompanying drawing in which a vertical section of an illustrative embodiment of the invention is shown. In the drawing reference character 1 indicates a bank of inclined tubes that are connected to down-take headers 2 and uptake headers 3. The down-take headers 2 are connected by down-take nipples 4 to the water space of the steam and water drum 5, and the upper portions of the headers 3 are connected by rows of steam circulating tubes 6 to the steam space of the steam and water drum 5.

A tube 7 connects the steam space of the steam and water drum 5 to the inlet header 8 of the superheater. The inlet header 8 is connected by the U-tubes 9 to the outlet header 10 and a connection 11 leads from this outlet header to the steam main.

A baffle 12 extends along the upper side of the uppermost row of inclined tubes 1 from the headers 2 to a position slightly beyond the inlet header 8. A baffle plate 13 extends across the superheater tubes 9 in front of the headers 8 and 10, and a baffle 14 extends from near the header 10 along the upper side of the uppermost superheater tubes so that a single gas pass is provided across the inclined tubes 1 and the superheater tubes 9. This baffle may vary in length, thus varying the size of the opening through which the gases pass after they cross the superheater tubes. The superheater tubes are supported by means of supports 15 that rest upon plates 16 upon the upper row of tubes 1.

The baffles 12, 13 and 14, constitute a composite baffle construction which is Z-shaped. This construction may be deemed the main baffle, and the baffle 17 the auxiliary baffle so arranged with respect to the main baffle that it encloses superheater headers in stagnant gases.

A baffle 17 extends from a position near the upper side of the outlet header 10 and is inclined downwardly and its lower edge 18 terminates some distance from the baffle 12 so that an opening is left between the baffle 17 and the headers 8 and 10 to provide communication between the space and the gas stream. Combustible gases will not, therefore, accumulate in this space and give rise to danger of explosion. The baffle is provided to prevent a stream of hot gases from flowing across the superheater headers and the space thus provided is large enough for a workman to gain access to the superheater headers 8 and 10 and the fittings on the headers. The gases in this space that contact with the headers reach approximately the temperature of the headers. A support 19 maintains the baffle 17 in position and the baffle 17 prevents the hot gases from impinging directly against the superheater headers. The gases pass over the tubes as indicated by the arrows and thence between the nipples 4 into the stack.

I claim:

1. In a water tube boiler, a bank of inclined tubes, a superheater above said bank of tubes having one header above the other, a baffle along the upper side of said superheater extending substantially to the upper header of said superheater, and a baffle extending in a downwardly inclined direction from the upper header of said superheater with its lower edge left free.

2. In a water tube boiler, a bank of inclined tubes, a baffle extending part way along said bank of tubes, a superheater above said bank of tubes having one header above the other, a baffle along the upper side of said superheater extending substantially to the upper header of said superheater, and a baffle extending in a downwardly inclined direction from the upper header of said superheater with its lower edge terminating short of said first named baffle.

3. Apparatus of the class described comprising, in combination, a water tube steam boiler having straight tubes, a furnace from which heating gases pass across the straight tubes for their entire length, a superheater

above said tubes, a Z-shaped baffle having one end part resting on top of the superheater and its remaining parts embracing the superheater headers, and a canopy baffle extending between said remaining parts to form a three sided box-like enclosure for the headers.

4. In steam generating equipment, a water tube steam boiler having straight boiler tubes, 10 a steam and water drum, downcomer nipples extending from the steam and water drum downwardly toward said tubes, a furnace underneath the boiler and causing heating gases to contact with said tubes over their 15 entire length, a steam superheater having tubes above the boiler tubes, inlet and outlet headers for the superheater, a Z-shaped baffle construction interposed between the furnace and the headers, and having a long end part 20 above the superheater and extending along the superheater tubes from said headers, and a roof construction including circulator tubes arranged above the baffle construction so as to compel the gases turning between the long 25 leg of the baffle and the roof to pass horizontally of the apparatus and leave between the downcomer nipples.

5. In a water tube steam boiler and its furnace, a bank of inclined tubes extending into 30 the path of the furnace gases, a first baffle extending part way along said bank of tubes, upper and lower superheater headers located above said bank of tubes, superheater tubes extending from said headers, a second baffle 35 along the superheater tubes and forming substantially an extension of the first baffle in defining a wall of the first gas pass, and a third baffle extending in a downwardly inclined direction from a position in which it 40 overlaps the upper header to a position wherein it terminates short of the first baffle and is spaced sufficiently from the lower header to afford access to the headers by an attendant.

45 6. In combination with a water tube steam boiler, a superheater having tubes exposed to hot gases, inlet and outlet headers connected to the tubes, a first baffle directing the gases in a first gas pass over the tubes and past the 50 headers without contacting with them, means for diverting the flow of gases leaving the superheater to a second gas pass on the side of the headers opposite to that occupied by the tubes, and a second baffle extending past 55 the headers in the direction of flow in the second gas pass to direct the diverted gases out of contact with the headers while providing a chamber open toward the downstream side with reference to gas movement 60 in the last gas pass and permitting access to the headers when the boiler is shut down.

7. In a water tube boiler, a bank of inclined tubes, a superheater above said bank of tubes having one header above the other, 65 a first baffle preventing impingement of fur-

nace gases from a first gas pass on the headers, and a second baffle located on the opposite side of the headers from the first and extending in a downwardly inclined direction from the upper header of said superheater with 70 its lower edge left free.

HOWARD J. KERR.
